UNITED STATES PATENT OFFICE.

FRANK E. SMITH AND GEORGE W. SMITH, OF MIDDLETOWN, NEW YORK.

WRENCH-LOCK.

1,148,410.

Specification of Letters Patent. Patented July 27, 1915.

Application filed March 11, 1915. Serial No. 13,624.

To all whom it may concern:

Be it known that we, FRANK E. SMITH and GEORGE W. SMITH, citizens of the United States, and residents of Middletown, in the county of Orange and State of New York, have invented a new and Improved Wrench-Lock, of which the following is a full, clear, and exact description.

This invention relates to wrenches and 10 has particular reference to wrenches having movable jaws.

Among the objects of the invention is to provide an easily controlled device or mechanism for preventing the undesirable movement of the movable jaw when it is necessary or required for such jaw to be retained in any predetermined position to which it may be adjusted as, for instance, for repeated operation upon the same nut or upon 20 a number of nuts of the same size.

The foregoing and other objects of the invention will hereinafter be more fully described and claimed and illustrated in the drawings forming a part of this specification 25 in which like characters of reference indicate corresponding parts in all the views, and in which—

Figure 1 is a side elevation of a well known form of wrench showing our invention applied thereto, a portion of the wrench being broken away on a vertical plane corresponding to the broken line 1—1 of Fig. 3; Fig. 2 is a side elevation of the same; Fig. 3 is a top plan view; and Fig. 4 is a longitudinal section on the line 4—4 of Fig. 1.

The several parts of this device may be made of any suitable materials, and the relative sizes and proportions, as well as the general design of the mechanism, may be 40 varied to a considerable extent without departing from the spirit of the invention hereinafter more fully described and claimed.

Referring more particularly to the drawings, we show a type of monkey wrench in which is a fixed jaw 10 and a movable jaw 11. The movable jaw is shown provided with a shank 12 extending at right angles to the active face of the jaw 11 and provided 50 with a series of teeth 13 coöperating with a worm 14 journaled upon a pivot pin 15 arranged parallel to said shank.

Without extending the description of the wrench mechanism *per se* unnecessarily, it 55 may be noted that the features thus far described are or may be of any well known or

suitable construction and furthermore that our invention is adapted to be applied to various specific types of monkey wrenches or other wrenches which involve relatively 60 fixed and movable jaws and controlled by a rotating screw or worm.

It is well known that after a wrench is used and laid aside, there is a common tendency for the screw or worm to be moved 65 or rotated with a corresponding variation in adjustment of the movable jaw of the wrench. Our purpose is to provide a simple and reliable form of locking device to prevent rotation of the worm and hence 70 a change of adjustment of the wrench. To this end we provide for the worm a circular series of teeth or notches indicated at 16 and shown herein as being arranged in a circle around one end of the worm. At 75 we show a keeper in the form of a lever of the first class pivoted at 18 in a cavity 19 formed in the handle or shank portion of the wrench adjacent the worm 14. One end of the keeper constitutes a finger 17' adapted 80 to enter any one of the notches 16, and when in such position will prevent rotation of the worm. The other end of the lever projects through a slot 20 beyond the wrench handle and terminates in a knob or other 85 suitable finger piece 21 whereby the lever may be swung far enough around its axis 18 to throw the finger 17' into or out of locking engagement with the worm. As a suitable means for holding the keeper in 90 either position to which it may be moved by the operation of the finger piece 21, we provide an angular extension 22 in the form of a triangle having its altitude extending from the pivot 18 substantially at a right 95 angle to the main or longer axis of the lever. The point of the projection 22 coöperates with a leaf spring 23 having its ends seated in notches at one end of the cavity 19. The spring permits the point of the extension 100 22 to ride over the angle formed in the middle portion of the spring, but the spring has force enough to prevent the accidental movement of the keeper in either direction. The finger piece 21, being within easy 105 reach of the operator's thumb or finger while manipulating the wrench, may be easily operated to either lock or unlock the wrench as occasion may require. If the lock is not needed at any particular time, it will 110 be swung out of contact with the worm and will so remain until it is returned to lock-

ing position by positive operation of the keeper. The cavity 19 is closed preferably by a face plate 24.

We claim:

5. 1. In a wrench, the combination with relatively fixed and movable jaws and a worm coöperating with the movable jaw and movable around an axis parallel to the direction of movement thereof, of a keeper 10 for the worm comprising a lever having at one end a finger adapted to engage the worm and having a projection extending from the lever pivot at an angle to the main axis of the lever, said extension terminating in a point, and a leaf spring having constant co-operation with said extension point and serving to hold the lever in either its locking or unlocking position.
2. In a wrench comprising relatively fixed 20 and movable jaws and a worm coöperating with the movable jaw for controlling its position, said worm having a series of teeth arranged in a circle around one end thereof, a keeper pivoted adjacent the worm and including a finger at one end adapted to move into the space between any two adjacent

teeth aforesaid, said keeper having a projection extending from the pivot thereof at an angle to the main part of the keeper, and a spring coöperating with said projection 30 and serving to hold the keeper in either its locking or unlocking position.

3. In a wrench, the combination with relatively fixed and movable jaws and a worm coöperating with the movable jaw and serving to control its position, said worm having a circular series of notches around one end, of a keeper adjacent the worm and including a finger movable into any one of said notches to prevent rotation of the worm, 40 said keeper including a finger piece accessible from outside of the wrench and a spring coöperating with the keeper to hold it in either its locking or unlocking position.

In testimony whereof we have signed our 45 names to this specification in the presence of two subscribing witnesses.

FRANK E. SMITH.
GEORGE W. SMITH.
